(57) CLAIM

The ornamental design for a shoe, as shown and described.

DESCRIPTION

FIG. 1 is a front left perspective view of a shoe showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the shoe shown in dot-dash broken lines in FIGS. 2, 3, 6, and 7 form no part of the claimed design. The portions of the shoe shown in even-dashed broken lines in FIGS. 3-6 represent threaded stitching and do form part of the claimed design.
